DESIGN FOR A HAND BAG FRAME

David Karron, Brooklyn, N. Y.

Application August 31, 1934, Serial No. 53,126

Term of patent 3½ years

To all whom it may concern:

Be it known that I, DAVID KARRON, a citizen of the United States, and a resident of Brooklyn, in the county of Kings and the State of New York, have invented a new, original, and ornamental Design for Handbag Frames, of which the following is a specification, reference being had to the accompanying drawing, forming part thereof.

Fig. 1 is a side elevation of a handbag frame, showing my new design.

Fig. 2 is an end elevation, and

Fig. 3 is a top plan view thereof.

I claim:

The ornamental design for a handbag frame, as shown.

DAVID KARRON.
